Gerald D. Lovell,
INVENTOR

BY J. W. Sheely
ATTORNEY

UNITED STATES PATENT OFFICE.

GERALD D. LOVELL, OF LOS ANGELES, CALIFORNIA.

METHOD AND APPARATUS FOR FIRING AND CONTROLLING STEAM BOILERS.

Application filed June 1, 1925. Serial No. 34,242.

The present invention relates to oil fired steam boilers and pertains more particularly to method and apparatus for firing and controlling steam boilers.

5 The invention has for its principal object, the provision of means for automatically regulating the amount of fuel fed to a boiler.

Another object of the invention is to provide simple and effective means for maintaining a predetermined steam pressure.

10 The invention contemplates the use of steam for atomizing the fuel, as well as for forcibly ejecting it from the burner, and it is therefore another object of the invention 15 to provide for closely and automatically regulating the amount of steam fed to the burner so that it will be in correct proportion to the amount of oil being used.

It is common practice in firing boilers with 20 liquid fuel to have the fuel supplied always at a constant pressure. Therefore it is advisable and often necessary to have the steam supplied to the burner at constant pressure.

Usually a pressure regulator or reducing 25 valve is employed for this purpose, and it is therefore another object of the invention to dispense with reducing valves and the like.

Still another object of the invention is to 30 provide simple, long-lived and efficient means for carrying out the objects of my invention, freedom from multiple adjustments being among the objects of this invention.

Still other objects and advantages of my 35 invention will appear hereinafter and will be better understood by virtue of the order in which they appear.

I have illustrated my invention by the accompanying drawings, in which:

40 Fig. 1 is a diagrammatic view showing the relative disposition of the various parts of an apparatus designed to carry out my invention.

Figure 2, is a vertical section of the principal unit of the apparatus.

45 Figure 3, is a view in section thereof on a line 3—3 of Fig. 2.

Figure 4, is a view in section on a line 4—4 of Fig. 2.

50 Figure 5, is a view mainly in vertical section of a modification of the units shown in Fig. 2.

Figure 6, is a cross section thereof on a line 6—6 of Fig. 5.

The burner includes a burner body 8, 55 which is internally provided with two valve seats 9 and 10 respectively, co-axially arranged one below the other.

The body includes two integral diametrically opposed hollow bosses 11 and 12, respectively, providing an oil inlet 13, and a steam inlet 14. The oil inlet continues to a fluid course 15 and the steam inlet continues into a steam passage 16. The steam passage and the oil passage 15 are separated from 60 each other throughout the length of the burner body. At the extreme tip 17 of the burner, the oil passage terminates in a central orifice 18 while the steam passage terminates in an annular orifice 19 surrounding said central orifice. Thus, as will be particularly apparent hereinafter, the oil is ejected from the burner in a small central stream surrounded by a more rapidly moving stream of steam which subdivides and 65 distributes the oil in conformance with accepted practice.

70 The steam passage leads to an annular opening 16 which leads to the main bore 21 of the burner body, just above the seat 9. 80 The burner further includes a stem 22 having a portion 23 of maximum diameter, which serves as a barrier between seats 9 and 10. Thus, oil flowing through the oil passage and annular opening 20, enters bore 21 85 and from there escapes through the valve seat 10 and through a central fluid course 18' to orifice 18. Portion 23 of the stem is also a guide for said stem and is a close running fit in bore 21. From guide 23 a 90 needle 24 of smaller diameter extends into fluid course 18' and co-acts with the valve seat 10 to predetermine the amount of fuel which will pass with a given pressure.

95 As will appear hereinafter, the oil flowing by valve seat 10 will be at practically the temperature of the steam and since the steam pressure is constant, the oil temperature will be constant and therefore the viscosity of a given fuel oil will remain constant.

100 From bore 21, or rather from the upper seat 9, a counter bore 25 continues to the top of the burner. The stem includes another enlarged portion 26, which is a close running fit in the counter bore 25. The steam passage leads into the counter bore just above seat 9. The stem, between the enlargements 105

23 and 26 is tapered, as at 27 and said taper co-acts with the seat to change the area of flow and to predetermine the amount of steam which may flow.

5 The needle 23 and the taper 26 are so proportioned relative to each other that at any given normal position of the stem, the area of flow of oil through seat 10, and the area of flow for steam through seat 9 are in what 10 has been found to be about proper proportion. Steam, having passed seat 9, is intercepted by guide 23. Below the seat 9, an annular opening 30 is provided, which allows the steam to escape to an annular passage 19', which leads to orifice 19.

Thus, a small single stem controls both the flow of oil and the flow of steam and by the construction just described, both the oil and steam are accurately metered. As the 20 stem is moved outwardly flow is increased. When the stem is moved inwardly, the needle and the tapered part of the stem simultaneously seat on corresponding seats and shut off the supply of oil and steam. 25 However, a suitable stop is arranged on the stem so that the supply of fuel is never entirely shut off, in order that a small pilot flame will always exist in the fire box.

For the purpose of automatically moving 30 the stem to automatically control the flow of fuel, I provide pressure actuated stem operating means in the form of a diaphragm regulator 32, said regulator includes a suitable adjustment, such as 33 controlling the compression of a spring 34, whereby the boiler pressure required to move the stem to closed position, is predetermined. The regulator is connected to a steam boiler 35 (see Fig. 1) by a steam line 36; a branch 37 of said line leading to the steam inlet.

Oil is supplied to the burner through an oil line 38 and said oil, as in usual practice, comes from a source of constant pressure.

45 In the operation of the complete apparatus, oil and steam are metered by the burner and become co-mingled at the burner tip. The resultant combustion of fuel under the boiler raises the boiler pressure. When the 50 desired pressure is reached, the regulator acts to depress the stem and the fuel supply is decreased. Obviously, the apparatus may be regulated to maintain a given boiler pressure. Since the boiler pressure remains constant, it follows that no reducing

valve or pressure regulator is required in the steam line leading to the burner. With steam pressure and oil pressure always constant, the proportion of oil and steam is always correct and therefore the minimum amount of steam, consistent with good combustion, is used for operating the burner.

It will be seen now that I have provided simple and efficient means for automatically firing a boiler at such rate as to maintain

constant boiler pressure, and by maintaining constant steam pressure and using the constant pressure steam to atomize the fuel, I provide for maximum efficiency in such use of steam, and while I have shown and described specific apparatus for carrying out my invention, and have described specific constructions for the parts of the apparatus, I do not limit myself to any specific construction or arrangements and 75 may alter same as I desire, or as occasion requires, without enlarging the scope of my invention within the appended claims.

I claim:

1. In a regulator of the class described, a regulator body provided with four internal cavities and a central bore extending from end to end of the body connecting all cavities and terminating in an oil discharge 95 orifice; said orifice opening into communication with the lowermost of the four cavities, the body being further provided with a steam inlet and a passage-way connecting the uppermost cavity with the said 90 steam inlet, the body further provided with a passage-way, other than the through bore connecting the lowermost cavity with the cavity second from the top, the body further provided with a fuel inlet and a passage-way connecting said fuel inlet and the cavity which is second from the bottom; the intersection of the bore and the uppermost cavity forming a steam valve seat, and the intersection of the bore with the second 100 cavity from the bottom forming an oil valve seat, and a stem terminating at its lower end in a conical end adjacent said oil valve seat; that portion of the stem between the two intermediate cavities fully occupying 105 the bore to isolate said two cavities from each other; that portion of the stem above the uppermost cavity likewise fully occupying the bore to isolate the uppermost cavity from points external to the body other than 110 the steam inlet, and that portion of the stem which is normally disposed between the uppermost and the next lower cavity being of reduced diameter and tapered with regard to said bore and coacting with the 115 steam valve seat, a movable wall above said body connected to said stem, and a fixed wall carried by said body and coacting with the movable wall to provide a steam pressure space.

2. A regulator as in claim 1, in which the steam space and the steam inlet in the body are in constant communication.

3. A regulator as in claim 1, in which the steam space and the steam inlet in the body are in constant communication by means of a bore through said stem ranging from, and in communication with, the uppermost cavity and the steam space, respectively.

4. In a regulator of the class described, a regulator body provided with a steam chamber and a valve seat in said steam chamber, and an oil chamber with a valve seat in said oil chamber, a passage-way connecting said chambers at points below both seats, a central bore through the body connecting said chambers, a stem fitting

closely in the bore between the chambers to isolate the chambers from each other, means 10 on said stem coacting with the seats to regulate flow of fluid; said stem movable vertically in said bore, and a diaphragm above said body attached to said stem.

GERALD D. LOVELL.
